UNITED STATES PATENT OFFICE.

EDWARD WITTCOFF, OF ST. LOUIS, MISSOURI, ASSIGNOR TO SUPERIOR HAT COMPANY,
OF ST. LOUIS, MISSOURI, A CORPORATION OF MISSOURI.

HAT.

Application filed June 13, 1928. Serial No. 284,957.

This invention relates generally to hats and, more particularly, to a certain new and useful improvement in hats of the type commonly known as harvest-hats.

5 Hats of the type stated are usually constructed with flexible relatively wide brims, and my present invention has for its object the provision in a harvest hat of means whereby a desired roll or curl in the brim may be 10 conveniently adjustably obtained.

And with the above and other objects in view, my invention resides in the novel features of form, construction, arrangement, and combination of parts hereinafter described 15 and pointed out in the claims.

In the accompanying drawing,—

Figure 1 is an elevational view of a hat constructed in accordance with and embodying my invention; and 20 Figure 2 is a cross sectional view through the middle of the hat, showing the co-operative relation between the brim and its curling chin-strap.

Referring now more in detail and by reference characters to the drawing, which illustrates a preferred embodiment of my invention, A designates the crown and B the brim of the hat, which is preferably constructed as a whole of straw or other woven fibrous material as is customary in the production of harvest or summer outing hats, the brim B being flexible and of relatively wide or transversely extended proportions.

C designates an adjustable holding or chin strap, whose middle portion is looped and passed through a slide-buckle or the like 1, whereby the strap C may be adjustably loosened and tightened at will. The end portions 2 of strap C are looped and passed slid-

ably through respective eyelets 3, 3, provided therefor in the brim B upon opposite sides of the hat, the ends of the strap C being brought under the brim and passed upwardly through eyelets 4 also provided therefor in the brim and knotted, as at 5, for securement, 45 as seen in Figure 3. It will be evident that by adjustably manipulating the chin strap C, the side portions of the brim B may be rolled upwardly and inwardly and thereby conveniently given a desired attractive curl. 50

Obviously, the general structure of the hat and the particular details of the manner of attaching the strap C may be modified and changed without in the least departing from the spirit and scope of the invention as defined in the appended claims. 55

Having thus described my invention, what I claim and desire to secure by Letters Patent is:

1. In combination with a hat having a transversely extended flexible brim provided at opposite sides of the hat with sets of spaced eyelets, a strap secured at its opposite ends to the brim and threaded through said eyelets for adjustably curling the brim upon itself. 60

2. In combination with a hat having a transversely extended flexible brim provided at opposite sides of the hat with sets of spaced eyelets, a strap secured at its opposite ends to the brim and threaded through said eyelets for adjustably curling the brim upon itself, 65 and means having engagement with the strap for retaining the same in brim adjusted position. 70

In testimony whereof, I have signed my name to this specification. 75

EDWARD WITTCOFF.
